UNITED STATES PATENT OFFICE.

MARVIN H. JESTER, OF DENVER, COLORADO, ASSIGNOR TO THE M. H. JESTER INVESTMENT COMPANY, OF DENVER, COLORADO, A CORPORATION OF COLORADO.

CLAMPING-CLIP MECHANISM FOR SECURING PLASTER-BOARDS TO METAL STUDDING.

1,234,903.

Specification of Letters Patent. Patented July 31, 1917.

Application filed January 12, 1914. Serial No. 811,709.

To all whom it may concern:

Be it known that I, MARVIN H. JESTER, a citizen of the United States of America, residing at the city and county of Denver and 5 State of Colorado, have invented a new and useful Clamping-Clip Mechanism for Securing Plaster-Boards to Metal Studding, of which the following is a specification.

My invention relates to a new clamping 10 clip mechanism for securing plaster boards to metal studding, the said plaster board metal stud partition being used in the form of a core that is adapted to receive and support plastering materials used in the construction of plastered partition walls in 15 buildings; and the objects of my invention are:

First, to provide a fire-proof plaster board supporting and clamping device for the 20 construction of partition walls for receiving plastering mortars and cements in the construction of plastered walls in buildings.

Second, to provide a plaster board clamping and supporting device that can be used 25 to support and secure plaster boards in partition form, and to secure them to the walls of buildings. And

Third, to provide a corner clamping device for turning angled corners in partitions 30 constructed of my plaster board supporting and clamping device.

I attain these objects by the mechanism illustrated in the accompanying drawings, in which:

35 Figure 1, is a perspective view showing a portion of a channel bar stud and plaster boards secured thereto, by the improved supporting and clamping clips.

Fig. 2, is an end view of the construction 40 shown in Fig. 1.

Fig. 3, is a horizontal sectional view on the line 3—3 of Fig. 2.

Fig. 4, is an end view similar to Fig. 2, but showing the clamping clip secured directly 45 over a supporting clip.

Fig. 5, is a top view of one of the clamping clips.

Fig. 6, is an elevation of a portion of a partition, embodying my invention and 50 showing wooden strips secured by the top and bottom rows of clamping clips, which are adapted to have secured thereto picture moldings and chair boards respectively.

Fig. 7, is a perspective view of a modified 55 form of clamping clip.

Fig. 8, is a horizontal sectional view, showing the application of the clip illustrated in Fig. 7.

Fig. 9, is a perspective view illustrating the style of clamping clip employed for securing the channel stud to the side of a door buck. 60

Fig. 10, is a horizontal sectional view of the construction shown in Fig. 9.

Fig. 11, is a perspective view of the clamping clip shown in Figs. 9 and 10, the said clip being secured to the door buck by means 65 of a nail.

Fig. 12, is a perspective view of a modified form of the clip in which the same is 70 provided with a pointed projection which is driven into the said door buck, thereby dispensing with the nail. And

Fig. 13, is a horizontal sectional view illustrating a style of supporting clip for 75 connecting the ends of plaster boards in forming corners.

Similar letters of reference refer to similar parts throughout the several views.

Referring to the drawings,— 80

The numeral 1 designates a channel iron stud of iron or steel. I preferably use one inch channel studs, as this size of channel makes a plastered partition that is one and three-quarters to two inches thick, and this thickness makes a partition that is stronger and cheaper and more sound-proof as well as vermin proof, than wooden partitions from four to six inches in thickness. Channel bars of smaller or larger sizes may be used, 90 however, if it is desired to make partitions of less or greater thickness than two inches. These channel bar studs take the place of wooden studs in wooden partition construction, and are positioned at such distances 95 apart vertically between the floor and ceiling beams of buildings as will support between them the size of plaster boards that are used in this class of fire-proof plastered partitions. The plaster boards that are used in this class of partition construction are made in sizes of various lengths and widths, the most general sizes made being 24, 30 and 36 inches long, and from 18 to 36 inches wide, and varying from one-quarter inch to 100 three-quarters of an inch in thickness. The channel bar studs are consequently set generally 18 or 24 or 30 or 36 inches apart, but can be set any distance apart to receive between them and their supporting clips plas- 110

ter boards that are made of any desired width.

The metallic studs used may be a flat bar of iron or steel as shown in my Patent Number 1,001,146, issued to me August 22, 1911, or it may be a channel bar of iron or steel as issued to me in my Patent No. 1,082,336, issued to me Dec. 23, 1913.

I preferably, however, use a channel bar 10 and preferably position them 24 inches apart, and preferably use plaster boards one-fourth of an inch thick and 24 inches wide and 36 inches long, although my improved plaster board supporting and clamping device can be made and positioned to support plaster boards of any thickness and of any length. The channel studs 1 extend from the floor joists 2, to the ceiling joist 3, and are secured thereto in any suitable manner. I preferably, however, bolt them at 20 their opposite end to a bar 4 of angle iron, by bolts 5. The bar 4 is secured by nails or screws that extend through holes in the angle bars to the floor and ceiling joist (see 25 Fig. 6). The channel bars are set edgewise across the length of the partition, and upon them are mounted at preferably eight inches apart, the supporting clips 6, and between each two adjacent clips I place a clamping 30 clip 7, which leaves about four inches from the center of each to the center of the supporting clips on each side of each clamping clip. The supporting clips are U-shaped 35 clips, and the free end portions of each clip are each provided with a laterally extending wing portion 8. These clips are formed of blank strips of iron or steel that are of a length to form the entire clip, and these strips are bent into their U-shape form and 40 the closed end portion of the yoke of the clip is formed to fit snugly over one edge of the channel bar, and against its edge, while the open or free ends of the yoke portion of the clip are arranged at such a distance 45 apart relative to the thickness of the edges of the channel bar as will cause them to be sprung over the edges of the channel bar and with sufficient resilient pressure to hold the clip by its elastic pressure at any point 50 along the length of the channel bar without slipping or falling from where it is placed by the operator.

The wings 8 are arranged and made deep enough to extend from one edge of the channel bar over its opposite sides, and may extend part way to or even with or a short distance beyond the opposite edge of the channel iron, as illustrated. The outer surface of its wings, at the outer edges of the 55 free ends of its yoke portion, extend beyond the opposite edge of the channel bar about an eighth of an inch, which is the preferred arrangement of my improved plaster board and metallic partition stud clamping device. 60 The wings 8 are made long enough to re-

ceive and support upon their inner surface the opposite ends of the plaster boards 9, which are placed against them after the channel bar studs have been secured in place to the floor and ceiling joists, and the supporting clips are placed on them at proper distances apart, as shown in Fig. 6. The plaster boards are started preferably at the floor and a plaster board is placed on each side of the channel stud, and against the 70 wings of the supporting clips a clamping clip is pressed by the operator against the plaster boards and is arranged to be pushed into engagement with and to lock with a frictional locking pressure against the adjacent edge of the channel bar stud. This 75 clamping clip forms the essential element of my present invention, and it comprises a channel shaped piece of sheet steel, iron or other suitable metal, that is made long 80 enough to extend over and beyond the opposite sides of the channel bar stud a sufficient distance to form a bearing of sufficient length against the plaster boards to clamp 85 them firmly against the plaster board. The 90 sides 11 and 12 of this channel shaped clip are provided with two slots 13 and 14, which extend from their edges to within about an eighth of an inch of the plate of the channel bar. These slots are arranged to leave narrow 95 side portions 16 between the top of the slots and the plate portion of the clip, which form truss members that stiffen the clip at its center above these slots. These slots 13 and 14 are made wide enough to permit the 100 clip to be placed over the edge of the channel bar stud loosely, and to bear against the plaster boards, and with the edges of its sides, while its plate portion stands about an eighth of an inch above the adjacent edge 105 of the channel bar stud, and from the inner ends of the slots 13 and 14 lateral slots 18 are formed in each side that are arranged to form two slightly tapering lips 20, which are arranged to engage the under side 22 of 110 the adjacent angled edge 23 of the channel bar stud, and wedge or force the clips' side edges down against the plaster boards 9. The ends 24 of the sides along the recesses, 115 extend into the channel space under the edge 23 of the channel bar stud. The edges of the sides of these clamping clips are so arranged relative to the slots 18 and the edge 23 of the channel bar and the surface of the 120 plaster boards, that when the operator wishes to apply the clamping clip he presses down on it hard enough to bend or spring the part of the plaster boards down enough 125 to allow the side lips 20 to be pushed under the edge 23 of the channel bar stud, and then when the pressure against the plaster board is removed, they will spring back into their natural position and will exert a resilient pressure against the clips and cause the lips 20 of the clips to bear with a clamping re- 130

slient pressure against the under side of the edge 23 of the channel bar, thus clamping the plaster boards to the supporting clips and to the channel bar stud.

5 These channel forms of clamping clips are provided with apertures 25 through their plate portions, which are made large enough to allow plastering mortar to flow easily through them into their channel space 10 between their sides. They are especially useful in supporting the opposite ends of wooden or other nail receiving grounds 21, which extend across the top portions of the partition to nail picture mold strips to, and 15 also close enough to the floor portion of the partition to nail base-boards and their molding member to. The grounds 21 have their ends arranged to extend into the open ends of the channel clamping clips, thus securely 20 holding them in position to be plastered into the partition.

I have illustrated grounds in Fig. 6, positioned to receive picture molding or nails for hanging pictures, and also for securing 25 base-boards and their moldings to, and they can be inserted wherever desired along the height of the partition.

While I have shown this channel form of clip made of plain smooth iron, it can also if 30 desired be made of corrugated iron or be provided with ribbed portions to strengthen it.

In Figs. 7 and 8, I illustrate a slight modification of the clamping clip. In this modification the arrangement of the channel bar 35 stud and the supporting clip is the same. The clamping clip itself, however, is formed of a ribbon strip of flat iron bent so as to form two flat oppositely extending wings 26 and 27 and upright angled sides 28 and 40 29 between the wings, the sides 28 and 29 being separated far enough apart to form a space 30 between them wide enough to allow them to pass loosely over the edge of the channel bar stud, and is also bent to 45 form an overhanging lip portion 31 having a space 32 between the folds in the metal that form the lip that is arranged to allow this hollow lip to be pushed over the side edge of the channel bar stud, and consequently 50 allows this hollow lip to incase the side and top and the under part of the adjacent edge of the channel stud. The lower edge of the fold in the strip that forms the overhanging lip is arranged with a down- 55 ward angled or wedge-shaped surface which with its overhanging lip is arranged to be pushed under the adjacent edge of the channel stud and bears against it and forces the wings of this clip to clamp themselves 60 against the adjacent surfaces of the plaster boards on opposite sides of the channel stud.

This ribbon-shaped clip is consequently placed over the edge of the channel stud and is pushed under its edge and clamps

against the under side of this edge and 65 against the ends of the plaster boards on opposite sides of the channel stud, the same as the channel form of stud shown in Figs. 1, 2, 3, and 4.

In Figs. 9, 10, 11, and 12, I illustrate an 70 adaptation of the clamping and supporting clip to the terminal ends of partitions to secure them to wooden grounds built into the walls of buildings. In this adaptation, I employ a supporting clip 33, having the 75 U-shaped stud engaging portion 34, and one plaster board supporting wing 35, the other wing being dispensed with. The supporting clip is sprung upon the stud, which abuts against the outside face of a door 80 frame or other wooden member 36, as shown, to which the adjacent end of the partition is to be secured, and in order to fasten the stud securely to the said door frame, I employ a combined stud supporting and plaster 85 board-clamping clip 37, which is constructed as follows:

The clip 37 is similar in cross-section to the clamping clip shown in the foregoing views, but it is provided on one end with 90 recesses 38, which receive one of the wings of the channel stud, this end of the clip being flush with the bottom member of the channel stud, when secured thereon, as will be understood by reference to Figs. 9 and 10, 95 so as to abut against the said door frame. The opposite end of the bottom of the clip is formed with parallel slits which extend inward a suitable distance, and that portion of the bottom released thereby is bent inward 100 at right angles, or so as to lie between the sides of the clip, to form a nail supporting plate 39, the plate being provided with a nail receiving aperture 40. When the clip is placed upon the channel stud, a space is 105 left between the bottom of the clip and the adjacent side of the stud, sufficient to permit a nail 41, which is inserted in the aperture 40, to pass between the bottom of the clip and the side of the channel stud, and be driven into the said door frame, as will be fully understood by reference to Fig. 10. By this method, the clip 37 not only serves 110 to clamp the plaster board against the wing 35 of the supporting clip 33, in like manner as the clip shown in Fig. 1, but it also serves to rigidly secure the channel stud to the buck 36, so that the end of the partition abutting against the said buck will also be 115 rigidly supported.

In Fig. 12, is illustrated a modification of the clip 37, comprising a clip 42, in which the nail supporting plate 39 is dispensed with, and the opposite end 43 of the bottom of the clip is extended beyond the sides thereof, and is V-shaped, as shown, the pointed end thus formed being driven into the door frame, and thus taking the place of the nail 120 125

41. The adjacent ends of the side members of this clip are provided with recesses 44, for the reception of one of the side members of the channel stud, the clip being adapted to engage the channel stud, and clamp the plaster boards thereto, the same as in the case of the clip 37.

Fig. 13 illustrates a corner clip 45 and the manner in which it is used to secure the adjoining ends of plaster boards in forming corners. In this connection an angle bar form of stud 46 is employed, and the clip is placed against the open side of the stud and bent around the same so as to lie against the sides thereof, the wings being then bent at right angles to the respective portions lying against the stud, and in line with the apex of the stud, as shown by 47, after which the remaining portions of the said wings are bent back parallel with the respective sides of the stud, as shown by 48, a space being left between the portions 48 and the portions which engage the stud sufficient to receive and hold the plaster boards without the employment of any additional means.

In operation, the studs are secured to the floor and ceiling, at predetermined intervals, and the supporting clips are sprung upon the studs, at suitable intervals, corresponding to the widths of the plaster boards, or the said clips may be secured to the studs as the work progresses, in position to form supports for the plaster boards which are laid against them, one above the other, from floor to ceiling. After the boards are placed, the clamping clips are placed over the studs and against the adjoining ends of a pair of boards, and then pressed to one side so that the edges of the recesses in their side members frictionally engage the adjacent side of the channel stud, whereby they are clamped to the said stud and against the adjoining ends of the plaster boards, which are thus clamped between the said clamping clip and the wings of the supporting clips. The supporting and clamping clips may alternate at regular intervals, or a clamping clip may be placed adjacent to a supporting clip, as shown by Fig. 6, or each clamping clip may be placed directly over a supporting clip, as shown in Fig. 4. When the plaster boards have all been secured, the usual rough and finishing coats of plaster are applied, thus completing the partition.

Having described my invention, what I claim as new and desire to secure by Letters Patent, is:

1. A support for plaster-boards, comprising a channel-bar stud, clips having U-shaped portions in frictional engagement with said stud and lateral extensions for supporting the plaster-boards, and clamping-clips comprising channel-plates the sides of which are recessed to engage one of the

sides of the stud, the sides of said clamping-clips extending inwardly to clamp the ends of plaster-boards against said lateral extensions.

2. A support for plaster-boards, comprising a channel-bar stud, clips in frictional engagement with said stud and having lateral extensions for supporting the plaster-boards, and clamping-clips in the form of channel-members, the side portions of said clamping-clips having recesses with inclined edges shaped to frictionally engage one of the sides of said channel-bar stud, said recessed sides extending inwardly to clamp the end portions of plaster-boards to said lateral extensions.

3. A support for plaster-boards, comprising a channel-bar stud, a supporting clip comprising a U-shaped member sprung upon said stud and having lateral extensions, and a clamping-clip comprising a channel-member the sides of which are provided with substantially L-shaped recesses frictionally engaging one of the sides of said stud, the engaging-faces of said recesses and the side of said stud being inclined, the sides of said clamping-clips extending inward toward said lateral extensions to clamp the ends of plaster-boards against said lateral extensions.

4. A support for plaster-boards, comprising a channel-bar stud, a supporting-clip having a U-shaped portion in frictional engagement with the stud and lateral extensions, and a clamping-clip comprising a channel-member having recesses extending from its inner edges toward the base of the channel, said recesses being of greater width than the depth of said channel-bar and terminating at their outer ends in right-angled branches having inclined inner marginal edges, said clamping-clip being placed upon the stud and pushed to one side, so that said inclined edges engage the inner edge of one of the sides of said stud, the sides of said clamping-clip serving to clamp the ends of plaster-boards to said lateral extensions.

5. A support for plaster-boards, comprising a channel-bar stud, a clip-plate frictionally engaging said stud and having portions to receive the inner faces of the plaster-boards, and a clamping-device comprising an integral plate having its central portion cut away to form a substantially L-shaped recess for receiving the outer portion of the stud, said integral plate having a portion frictionally engaging the inner side of the outer flange of said channel-bar stud and wing-portions for engaging the outer faces of the plaster-boards to maintain the latter against said clip-plate.

6. A support for plaster-boards, comprising a channel-bar stud, a U-shaped clip-plate fitting around the outer edge of and frictionally engaging said stud and having

wings at its free ends to receive plaster-boards against their outer faces, and a clamping-device comprising an integral plate having its central portion cut away 5 to form a substantially L-shaped recess for receiving the outer portion of the stud, said integral plate having a portion frictionally engaging the inner side of the outer flange of said channel-bar stud and wing-portions 10 for engaging the outer faces of the plaster-boards to maintain the latter against said clip-plate.

7. A support for plaster-boards, comprising a stud having a flange along its outer 15 edge, clips in frictional engagement with said stud and having integral lateral extensions for supporting the plaster-boards; and clamping clips having outer portions embracing said outer flange of said stud and

portions extending inwardly from said outer 20 portions for maintaining the plaster-boards against said lateral extensions.

8. A support for plaster-boards, comprising a stud having a flange along its outer edge, clips in frictional engagement with 25 said stud and having integral lateral extensions for supporting the plaster-boards, and clamping clips having outer portions wedged between said flange of the stud and the plaster-boards to maintain the plaster- 30 boards against said lateral extensions.

In testimony whereof I affix my signature in presence of two witnesses.

MARVIN H. JESTER.
